UNITED STATES PATENT OFFICE.

ANDREW F. SHULER, OF ARCANUM, OHIO.

SIDE-BAR VEHICLE.

SPECIFICATION forming part of Letters Patent No. 259,595, dated June 13, 1882.

Application filed March 22, 1882. (No model.)

To all whom it may concern:

Be it known that I, ANDREW F. SHULER, of Arcanum, of Darke county, and State of Ohio, have invented a new and Improved Running-Gear and Springs of Side-Bar Buggies; and I do hereby declare that the following is a full, clear, and exact description of the same, reference being had to the accompanying drawings, forming part of this specification, in

10 which—

Figure 1 is a perspective view of my invention; Fig. 2, a transverse section on line x x , Fig. 1; and Fig. 3 is a detail view.

My invention relates to improvements in the running-gear and springs of side-bar buggies; and it consists in the peculiar construction and arrangement of the parts, as hereinafter more fully set forth.

In the accompanying drawings, a represents 20 the front and b the rear axle of my improved buggy.

c represents the front cross-bar, pivoted to the front axle in the usual manner by a king-bolt, d , which passes through holes in the centers of the front cross-bar and front axle, and also through holes in the opposite parallel 25 arms of the clevis e , the upper arm of the clevis being inserted in a slot, h , in the middle of the front cross-bar, c , and the lower arm of the 30 clevis lying under the lower face of the front axle, a .

i i represent the side bars of my improved buggy, secured near the ends of the front cross-bar, c , at their forward ends, and attached 35 to the rear axle, b , near their rear ends.

k k represent angular side braces, secured to the axle b near their outer ends, and having their opposite ends secured to the side bars, i i .

40 l l represent the front springs, each consisting of a flat spring, one end of which is secured to a side bar i near to its front end, and is thence curved downwardly and then upwardly to the under face of the bottom of the 45 buggy-body o , to which it is secured. The spring l is thence bent downwardly and then curved upwardly, with its opposite end resting under the bottom of the buggy-body near its opposite side. The other front spring l is 50 parallel, and lies near the spring just described,

and is secured to the opposite side bar i and the bottom of the buggy, and runs in an opposite direction, as shown in the drawings.

m m represent the hind springs, secured to the opposite side bars i , and precisely similar 55 in construction and arrangement to the front springs, l , just described. The front and hind springs, l m , may be provided with any desired number of leaves.

p represents a brace-rod secured to the head 60 of the bolt q , which secures the front spring, l , to one of the side bars i . The brace-rod p passes thence through the clevis e , around the king-bolt d , and thence to the opposite bolt, q , which secures the opposite spring l to the 65 opposite side bar i .

What I claim as my invention, and desire to secure by Letters Patent, is—

1. The combination, with the side bars, i i , of the front springs, l l , and rear springs, m m , 70 having a spring of each pair secured at one end to one of the side bars, and thence curved downwardly and upwardly and secured to the bottom of the buggy-body, and having the other two springs of each pair secured to the 75 opposite side bar i at their outer ends, and thence curved downwardly and upwardly and secured to the buggy-bottom, substantially as described, and for the purpose set forth.

2. The combination, with the front axle, a , 80 front cross-bar, c , having slot h , king-bolt d , clevis e , side bars, i , and front springs, l , secured to the opposite side bars at one end and to the buggy-body, of the brace-rod p , secured at its ends to the side bars, and passing through 85 the clevis and around the king-bolt, substantially as described, and for the purpose set forth.

3. The combination of the front and rear axles, a b , slotted front cross-bar, c , king-bolt 90 d , clevis e , side bars, i , brace-rod p , front and rear springs, l l and m m , constructed and arranged as shown, and brace-rods k k , substantially as described, and for the purpose set forth.

ANDREW F. SHULER.
